UNITED STATES PATENT OFFICE

GEORGE A. ISENMAN AND GUSTAF I. JOHNSON, OF MALDEN, MASSACHUSETTS, ASSIGNEES TO AUTOMATIC FLOOR WAXING MACHINE CORPORATION, OF MALDEN, MASSACHUSETTS, A CORPORATION OF MASSACHUSETTS

FLOOR WAXING AND POLISHING MACHINE

Application filed August 15, 1928. Serial No. 299,682.

Our present invention relates to machines for treating floors, and more particularly to novel machines for waxing and polishing floors.

5 An important object of the present invention is the provision of a machine by means of which floors may be waxed and polished, regardless of their size or area, in a relatively short space of time.

10 Another object of the invention is to provide a machine to accomplish these results which will be economical to manufacture, simple to construct and assemble, and easy to operate.

15 Our present machine is capable of use with either solid or liquid wax, but we preferably utilize solid wax, since the inherent qualities of solid wax for polishing purposes are far superior to liquid wax, which of necessity has non-waxing substances therein.

20 We utilize, in our novel machine, a rotary brush having a pulley on each end thereof, said brush being driven by suitable means, such as belts, from pulleys mounted on a suitable motor.

25 Another feature of the invention resides in carrying the weight of the machine on rolling elements, the brush contacting with the floor but not being subject to the pressures and strains which would be present if the weight of the machine were borne by the brush. This greatly relieves the load carried by the motor, and enables the use of a relatively small motor to cause the high speed of rotation of the brush required for efficient waxing and polishing.

30 Another feature of the invention resides in providing a novel motor support, wherein the motor is mounted on a pair of pivots.

35 40 Bearing against the motor is a spring of suitable size and strength to swing the motor on its pivots and thus constantly retain proper tension on the brush driving belts.

45 50 A further novel feature of the present invention resides in the mounting for the brush. Said brush is pivotally mounted in such manner as to permit of slight vertical oscillation thereof. Thus, when an obstruction is encountered on the floor during the waxing or polishing operations, the brush will

be raised thereover, without injury to the brush, and without detracting from the waxing and polishing action of the brush.

55 Another object of the invention is the provision of means to heat the wax to the desired degree to permit said wax to flow through the machine and onto the brush.

A still further object of the invention resides in the provision of means whereby the brush itself will aid and assist in the feeding 60 of the wax to said brush.

65 Another and important object of the invention is to provide means for properly distributing the molten wax over the surface of the brush prior to contact of the waxed portion of the brush with the floor.

70 A further feature of the invention resides in providing means to effect a preliminary cleaning of the brush as each portion of the surface of said brush leaves the floor, this preliminary cleaning means removing lint or any large pieces of dirt from the bristles of the brush before re-entry into the machine of those parts of the surface of the brush which have contacted with the 75 floor.

76 Another feature resides in the provision of means, such as a scraper, arranged to engage the outer edges of the bristles of the brush and effect a final cleaning of the same before said bristles engage the wax openings or nozzles. Thus the bristles of the brush will be clean and in proper condition for assisting in drawing the wax from the feed openings.

81 85 Another object of the invention is the provision of novel means to control the feeding of the molten wax from the wax pot to the brush. This controlling means may be manually or pedally operated.

86 90 Another feature resides in the provision of means to control the amount of wax which flows into the said feeding means.

95 A still further feature of the invention consists in having the switches for control of the motor, as well as for the control of the wax heating unit, on an operating handle within easy reach of the operator.

100 Our present novel machine is efficient, compact, speedy of operation, durable and rugged.

We believe that said machine, as above briefly described, and as hereinafter more fully described, is novel, and have therefore claimed the same broadly in the present application.

The above and further objects of the invention, features, details of construction, combinations of parts, and advantages, will be hereinafter more fully pointed out, described and claimed.

Referring now to the drawings, illustrating a preferred embodiment of our present invention,

Fig. 1 is a side elevation of our novel floor waxing and polishing machine;

Fig. 2 is a front elevation of the machine illustrated in Fig. 1;

Fig. 3 is a longitudinal sectional view on the line 3—3 of Fig. 2;

Fig. 4 is a cross-sectional view on the line 4—4 of Fig. 3, illustrating the pivoted motor support; and

Fig. 5 is a perspective view, on an enlarged scale, of the wax feeding valve or tube and operating lever or handle therefor.

Referring now to the drawings, for a particular description of the invention, its construction and operation, 1 designates a frame or hollow casing within which a brush 2 is mounted on a pair of arms 3, said arms being pivotally mounted at 4 to the sides of the casing 1. The casing 1 is mounted on rollers or casters 5, and the brush 2 extends below the casing a sufficient distance to contact with the floor or surface being waxed or polished. Because of the pivotal mounting of the arms 3 carrying the brush 2, if an obstruction or unevenness is encountered by the brush in its passage over the floor, the brush may be oscillated a sufficient amount to prevent injury thereto, while at the same time efficiently and properly waxing or polishing the surface.

The brush 2 is provided with a pulley 6 at each end thereof. Pivotally mounted within the casing 1 is a motor 7 having at each end a pulley 8 preferably having a cork or other friction facing 9. A belt 10 is arranged extending from each pulley 8 to the cooperating pulley 6 on the brush, said pulleys 8 being, of course, rotated by the motor.

The motor is pivotally mounted on screws 11 each having a pointed end 12 seating in a recess 13 in the motor casing, said screws extending through suitable bosses 14 in the casing 1 and being held in properly adjusted position by locking nuts 15.

Abutting against the motor 7 and at one side thereof is an arcuate plate 16 having thereon a plunger 17, a spring 18 surrounding said plunger, and said plunger and spring being seated in a suitable recess 19. The spring exerts pressure against the motor 7, swinging it on its pivot, and constantly keeping the proper driving tension on the belts 10.

It will be noted, from a glance at the draw-

ings, that the pivot point 4 of the arms 3 is above the center line of the motor 7, and that the pivot point of the brush 2 is below the center line of said motor 7. Thus, pressure of the spring 18 against the motor will swing said motor about its pivot 12, thus forcing the brush 12 downwardly. In this manner constant and efficient rotation or driving of the brush 2 is assured as well as pressure thereof on the floor or other surface being operated upon.

Mounted within the casing 1 is a wax pot or wax container 20 secured to lugs 21 by screws 22. Fixed in a boss 23 in the wax pot 20 is a post 24 having its upper end threaded at 25. Adapted to seat over said post is a removable cover 26 having shoulders adapted to seat on the top of the casing 1 and a knob 27 is adapted to be screwed onto the post 24 to firmly hold said cover 26 in place, a gasket 28 being interposed between the top of the wax pot 20 and the lower rim of the cover 26. An aperture 29 is provided leading from the wax pot 20 to a tube 30 having an aperture 31 therein adapted to be alined, at the will of the operator, with the aperture 29. A lever or handle 32 is provided at one end of said tube 30 for rotating the same, and said lever may be operated either by hand or by foot, as desired, to open or closed position, or to any intermediate position.

Extending obliquely through the bottom of the wax pot 20 are a series of channels 33, and in the tube 30 are a plurality of apertures 34 adapted to be alined, on operation of the lever 32, with said channels 33.

The channels 33 lead to a position where the wax will be dropped onto the brush 2. A suitable electrical heating unit 34 is arranged in the bottom of the wax pot 20 and in close juxtaposition with the tube 30. Thus, when solid wax is utilized, as is preferable, the heating unit 34 will melt the wax remaining in the tube first, and the heat will then permeate and melt the wax in the pot 20. A manually operated needle 35 is provided to control the flow of the wax through the aperture 29 to any desired degree.

Located under the wax pot 20 is an arcuate plate 36, this plate extending partially around and contacting with the brush 2 at 37. In the plate 36 are a plurality of openings 38, each opening having a lip 39 at one side thereof, the brush 2 contacting with said lips, and, by capillary attraction, aiding the flow of the wax through the openings 38. The plate 36 will effect an even distribution of the melted wax over the face of the brush so that the surface of the brush will be completely waxed along its length before it contacts with the floor 40. A plate 41 is attached to the bottom front edge of the casing 1 and spaced slightly from the surface of the brush 2. This plate will effect a preliminary cleaning action of the brush 2, and will remove there-

from all large particles of dirt, lint, thread or the like. The upper end of the plate 36 is bent downwardly as at 42, and is adapted to contact with the surface of the brush 2 to effect a final cleaning or scraping thereof before the brush contacts with the lips 39, thus insuring that the surface of the brush will be cleaned before a new supply of wax is distributed thereover.

When it is desired to merely polish the floor 40, after having waxed the same, the lever 32 will be operated to disaline the apertures 34 from the channels 33 and thus prevent the further flow of wax to the brush, said brush then being rotated and acting merely as a polishing device.

Suitable current conducting wires 43 lead from the heating unit 34 to a switch 44 on the hollow handle 45, the wires 43 passing through said handle. Current conducting wires 46 lead from the motor 7, through the handle 45, to a switch 47 on the handle 45. Each of these switches 44 and 47 are within easy reach of the operator. A wire 48 of any desired or suitable length and having a plug 49 on one end, is provided, for attaching to a receptacle or socket for securing power. Cleats 50 are provided for winding the wire 48 on the handle 45 in a compact, neat manner.

The lower end of the handle 45 is provided with two arms 51 pivotally secured to lugs 53 on the casing 1, and when the handle 45 is in upright position, said arms 51 will snap into recesses 52 in said lugs 53, thus holding the handle 45 in its upright position.

It will be appreciated that we have devised a novel, simple, efficient, compact, and desirable machine of this character, and one which is possessed of many advantages and features of utility.

While we have necessarily described our present invention somewhat in detail, it will be appreciated that we may vary the size, shape and arrangement of parts within reasonably wide limits without departing from the spirit of the invention.

Our invention is further described and defined in the form of claims as follows:

1. In a machine of the kind described, a pivotally mounted rotatable brush, a pivotally mounted motor, means operated by said motor to rotate said brush and effect a downward pressure thereon, a wax container, means to feed wax from said container to said brush, and means to distribute said wax over the surface of said brush.

2. In a machine of the kind described, a pivotally mounted rotatable brush, a pivotally mounted motor, flexible driving elements operated by said motor to rotate said brush, a wax container and spring controlled means extending from said container and bearing against said motor to constantly keep said driving elements under proper

tension to effect a downward pressure on said brush.

3. In a machine of the kind described, a pivotally mounted rotatable brush, a pivotally mounted motor, flexible driving elements operated by said motor to rotate said brush, a wax container, spring controlled means extending from said container and bearing against said motor to constantly keep said driving elements under proper tension, said means automatically forcing said brush in a downward direction, means to heat the wax in said container, means to feed wax from said container to said brush, and means to distribute said wax over the surface of said brush.

4. In a machine of the kind described, a rotatable brush, a pivotally mounted motor, flexible driving elements operated by said motor to rotate said brush, spring means bearing against said motor to constantly keep said driving elements under proper tension, a wax container, means to heat the wax in said container, means to feed wax from said container to said brush, an arcuate plate affixed to said container and extending partially around and contacting with said brush to distribute said wax over the surface of said brush, and means to clean said brush before application of the wax thereto.

5. In a machine of the kind described, a rotatable brush, a pivotally mounted motor, flexible driving elements operated by said motor to rotate said brush, spring means bearing against said motor to constantly keep said driving elements under proper tension, a wax container, means to heat the wax in said container, means to feed wax from said container to said brush, an arcuate plate affixed to said container and extending partially around said brush, one end of said plate contacting with said brush to distribute said wax over the surface of said brush, means to effect a preliminary cleaning of said brush, and the other end of said arcuate plate contacting with said brush to effect a final cleaning or scraping of said brush before application of the wax thereto.

6. In a machine of the kind described, a rotatable brush, a pivotally mounted motor, flexible driving elements operated by said motor to rotate said brush, spring means bearing against said motor to constantly keep said driving elements under proper tension, a wax container, means to heat the wax in said container, means to feed wax from said container to said brush, an arcuate plate bearing against said brush and adapted to distribute said wax over the surface of said brush, and spring means to retain said arcuate plate in contact with said brush.

7. In a machine of the kind described, a rotatable brush, a pivotally mounted motor, flexible driving elements operated by said

motor to rotate said brush, spring means bearing against said motor to constantly keep said driving elements under proper tension, a wax container, means to heat the wax in said container, means to feed wax from said container to said brush, an arcuate plate bearing against said brush and adapted to distribute said wax over the surface of said brush, and spring means to retain said arcuate plate in contact with said brush, said arcuate plate having a plurality of apertures therethrough, said brush traversing said apertures to increase the flow of wax therethrough.

8. In a machine of the kind described, a pivotally mounted rotatable brush, a pivotally mounted motor, flexible elements connecting said motor and said brush and adapted to rotate said brush, spring means bearing against said motor to keep said flexible elements under proper tension, a wax container, means to heat the wax in said container, a plurality of channels leading to said brush, means to feed a predetermined amount of wax through said channels to said brush, an arcuate plate engaging said brush and adapted to distribute said wax over the surface of said brush before contact of the waxed surface of the brush with the floor, said arcuate plate having a plurality of apertures therethrough aligned with the said channels, said brush traversing said apertures to increase the flow of wax therethrough, a spring plate bearing against said arcuate plate to maintain the engagement of said arcuate plate with said brush, and means to clean the surface of said brush before application of the wax thereto.

9. In a machine of the kind described, a pivotally mounted rotatable brush, a pivotally mounted motor, flexible elements connecting said motor and said brush and adapted to rotate said brush, spring means bearing against said motor to keep said flexible elements under proper tension, a wax container, means to heat the wax in said container, a plurality of channels leading to said brush, means to feed a predetermined amount of wax through said channels to said brush, an arcuate plate engaging said brush and adapted to distribute said wax over the surface of said brush before contact of the waxed surface of the brush with the floor, a spring plate bearing against said arcuate plate to maintain the engagement of said arcuate plate with said brush, means to clean the surface of said brush before application of the wax thereto, a frame within which the foregoing mechanism is mounted, and rollers on which said frame is carried, substantially the entire weight of said machine being borne by said rollers.

10. In a machine of the kind described, a pivotally mounted rotatable brush, a pivotally mounted motor, flexible elements con-

necting said motor and said brush and adapted to rotate said brush, spring means bearing against said motor to keep said flexible elements under proper tension, a wax container, means to heat the wax in said container, a plurality of channels leading to said brush, a projecting lip at the exit of each of said channels adapted to be engaged by said brush to accentuate the flow of wax from said channels, means to feed a predetermined amount of wax through said channels to said brush, an arcuate plate engaging said brush and adapted to distribute said wax over the surface of said brush before contact of the waxed surface of the brush with the floor, a spring plate bearing against said arcuate plate to maintain the engagement of said arcuate plate with said brush, and means to clean the surface of said brush before application of the wax thereto.

In testimony whereof, we have signed our names to this specification.

GEORGE A. ISENMAN.
GUSTAF I. JOHNSON.
